MEANS FOR APPLYING METAL FERRULES
TO FIBER CONTAINERS

Charles T. Walter, Chicago, Ill., assignor to Industrial Patents Corporation, Chicago, Ill., a corporation of Delaware

Original application May 29, 1936, Serial No. 82,433. Divided and this application February 23, 1937, Serial No. 127,256

1 Claim. (CL 153—1)

This invention relates to means for applying metal ferrules to fiber containers.

This application is a division of my copending application Serial No. 82,433, filed May 29, 1936, entitled Paper can.

One of the objects of the invention is to provide an improved means for applying metal ferrules to fiber containers.

Other objects of the invention will be apparent from the description and claim which follow.

In the drawings similar reference characters in the several figures designate similar parts.

Figure 1 is a plan view of a metallic strip formed into a circle.

Figure 2 is a side view of the metallic strip shown in Figure 1.

Figure 3 is a plan view of the metallic strip shown in the previous figures after it has been flanged.

Figure 4 is a sectional view on line 4—4 of Figure 3.

Figure 5 is a sectional view of a cupped fiber disc.

Figure 6 is a diagrammatic plan view of a machine arrangement for automatically assembling paper cans.

Figure 7 is a sectional view showing a cupped disc in the position in which it is fed to an open can body.

Figure 8 is a view, partly in section, showing the feeding of a metallic ring to the station of the assembling machine.

Figure 9 is a side view, partly in section, showing a ring in position on a chuck above a can body.

Figure 10 is a side view, partly in section, showing a cupped disc in a metallic ring in position with respect to the can body preparatory to seaming.

Figure 11 is a sectional view of a seaming chuck employed in seaming a container employing the ferrule involved in this invention.

Figure 12 is a sectional view of a modified type of seaming chuck employed in applying a modified form of ferrule omitting the inner peripheral flange.

The ferrule employed in the present invention is prepared from a narrow strip of tin plate formed into a circle with the ends joined together to form a substantial ring as shown in Figures 1 and 2.

It will be noted that the ends of the ferrule 1 are joined by lock seam 2 which embraces only the central portion of the ring. Within the area of the lock seam there are four layers of metal

and to facilitate flanging the lock seam terminates somewhat short of the edges 3 and 4. The ferrule 1 is first bent as shown in Figures 3 and 4 to form outwardly extending flange 5 and inwardly extending flange 6. The area embraced by lock seam 2 is not flanged. Outwardly turned flange 5 provides metal for crimping over the can body. Inwardly turned flange 6 provides depth control for the metallic ferrule with respect to the seaming chuck and forms a flat guide surface to permit adjacent covers to rest and slide upon each other in the cover feeding mechanism.

Figure 5 illustrates a cupped fiber disc having a flat disc portion 7, upwardly extending walls 8, and flange 9.

The manner of automatically assembling paper cans is shown in Figure 6 in which framework or turret 10 rotates about shaft 11 in the direction of the arrows. Turret 10 carries a number of can seaming stations 12. Each station comprises 20 a lower rotatably mounted can body supporting table 13 and a rotatably mounted seaming chuck 14 as is more particularly shown in Figures 8, 9 and 10.

Tubular fiber can bodies 15 are delivered to the machine by conveyor 16 so that as each station 12 passes the conveyor input it picks up an open can body 15. Adjacent to the can body feed conveyor 16 and positioned above it is a ferrule feeding conveyor 17 arranged with respect to the seaming chucks 14 as shown in Figure 8. The conveyor 17 and shuttle 18 are of the conventional type. As each station passes ring shuttle 18, seaming chuck 14 picks up a metallic ring 1 as shown in Figure 8 in which ring 1 is shown resting on shuttle 18 in a sloping position with respect to the plane of motion of chuck 14. The shuttle 18 is flexible so as to permit ring 1 to be readily withdrawn by chuck 14. Ring 1 is shown in position on chuck 14 in Figure 9. Adjacent to conveyor 17 is a second feeding conveyor 20 which serves to deliver cupped fiber discs 21 to the seaming chuck. Conveyor 20 is also equipped with an automatic feeding device at 22. Both feeding devices 19 and 22 feed their respective objects from a stack arranged with the objects stacked in piles with the flanges of each pile in contact.

Conveyor 20 is equipped with shuttle 23. The arrangement of conveyors and sloping shuttles shown in Figure 6 is conventional. As each seaming station moves from conveyor 17 to conveyor 20, seaming chuck 14 carries with it a metallic ring 1. At shuttle 23 each station picks up a cupped paper disc 21 as indicated in Figure 7. The seaming chuck now holds a metallic ring 55

1 under which is placed a cupped disc 21. These
2 two objects are now in a position to be placed into
3 the can body preparatory to seaming, which op-
4 eration is illustrated in Figure 11, at which sta-
5 tion the outer flange 6 is crimped over the outer
6 edge of the can body.

7 Figure 11 shows a seaming chuck having a
8 seaming roll 24 of typical cross section. Seaming
9 roll 24 has a conical surface 25 which ex-
10 tends to a point closer the center of rotation of
11 can body 15 than edge 26 of the seaming chuck
12 14. Extended conical surface 25 engages the
13 straight surface of outward flange 6 before it is
14 crimped to cause it to positively assume a con-
15 cave curvature downwardly. It will be clear,
16 therefore, that the thickness of surface 26 can
17 not be substantially relatively greater than shown
18 in Figure 11. Therefore, in order to control the
19 depth at which chuck 14 can enter ring 1 and at
20 the same time exert a downward pressure between
21 ring 1 and can body 15, inwardly turned flange
22 6 must be provided. If inward flange 6 were not
23 provided and the metallic ring 1 were the type
24 shown in Figure 12, chuck 14 would not exert
25 the necessary pressure between the can cover
26 and can body. If it is desired to eliminate flange
27 6 from the metallic ring and employ a ring of
28 the type shown in Figure 12, seaming chuck 14
29 may be modified to accommodate the conditions
30 as shown in Figure 12 where working surface 27
31 is provided with an outwardly tapered upper ex-
32 tremity 28 designed to engage the correspond-
33 ingly curved surface of ring 1 in such a manner
34 as to exert a downward force between the can
35 cover and the can body and yet at the same time

clear the conical extension 25 of the seaming
35 chuck.

I claim:

5 In a can seaming device for applying a cupped
fibrous end to a fibrous tubular body by means
of a metallic ferrule, the ferrule comprising a
vertical wall adapted to fit within the cupped
fibrous end and a flanged wall bent outwardly
10 from the vertical wall, the flanged wall being
adapted to extend above the end edges of the
cupped end and tubular body and beyond the
outer wall of the tubular body to provide a por-
tion adapted for crimping to the outer wall of
15 the tubular body, the edge joining the vertical
wall with the flanged wall providing a curved
outer surface, the combination of a seaming chuck
adapted to engage the inner surface of the ver-
tical wall and provided with an outwardly curved
20 upper peripheral surface designed to engage the
curved edge joining the vertical wall with the
flanged wall and to press the ferrule and fibrous
end within the end of the tubular body, and a
seaming roll rotatably mounted in operative re-
lation with the seaming chuck provided with an
extended conical surface adjacent its upper pe-
25 ripheral edge, the conical surface being operable
to engage the portion of the flanged wall ex-
tended beyond the tubular body to cause it to
assume a concave curvature downwardly before
30 crimping to the outer wall of the tubular body
and simultaneously to engage the portion of the
flanged wall extended above the end edges of the
cupped end and tubular body to prevent upper
bowing of the last-mentioned portion of the
35 flanged wall during the crimping operation.

CHARLES T. WALTER.
